CONTROLLED TEMPERATURE CHAMBER FOR
MATERIALS TESTING OR SIMILAR USE

Allen R. Williams, Jr., South Lynnfield, Mass., assignor
to Instron Corporation, Canton, Mass., a corporation
of Massachusetts

Filed Feb. 8, 1965, Ser. No. 83,707

Term of patent 14 years

(Cl. D16—2)

FIG. 1 is a perspective view of a controlled temperature chamber for materials testing or similar use embodying my new design;

FIG. 2 is a top plan view thereof;

FIG. 3 is a rear elevation thereof; and

FIG. 4 is an elevation as seen from the left of FIG. 1.

The dominant features of my design reside in the full line portions.

I claim:

The ornamental design for a controlled temperature chamber for materials testing or similar use, substantially as shown and described.
